US00D552599S

(12) **United States Design Patent** (10) **Patent No.:** **US D552,599 S**
Krzyzanowski et al. (45) **Date of Patent:** **** Oct. 9, 2007**

(54) **PORTION OF A REMOTE CONTROLLER**

(75) Inventors: **Paul Krzyzanowski**, Flemington, NJ (US); **Justin Flores**, Boca Raton, FL (US)

(73) Assignee: **OpenPeak Inc.**, Boca Raton, FL (US)

(**) Term: **14 Years**

(21) Appl. No.: **29/241,999**

(22) Filed: **Nov. 4, 2005**

Related U.S. Application Data

(63) Continuation of application No. 29/236,612, filed on Aug. 19, 2005.

(51) **LOC (8) Cl.** **14-03**

(52) **U.S. Cl.** **D14/218; D14/247**

(58) **Field of Classification Search** D14/174, D14/137-139, 151, 217, 218, 191-193, 167, D14/299, 168, 247, 455, 456; D13/168, 162-164; D21/512-517, 566; D10/104, 106; 345/169; 348/114, 734; 455/352-355, 151.1-151.4, 455/128, 347, 90.3

See application file for complete search history.

CLAIM

The ornamental design for a portion of a remote controller, as shown and described.

DESCRIPTION

FIG. 1 is a perspective view of a portion of a remote controller showing our new design; and,

FIG. 2 is another perspective view thereof at an enlarged scale.

The broken lines are environmental only and form no part of the claimed design.

1 Claim, 2 Drawing Sheets
